BOX WITH COVER AND HINGE THEREFOR

Hans H. Wanders, Hingham, Mass.

Application June 25, 1932, Serial No. 619,282

10 Claims. (Cl. 217—57)

This invention relates to a hinge especially adapted for use in connecting covers to boxes. The invention furthermore relates to structure or formation of the portions of the box and cover adjacent to the hinge whereby the hinge may be quickly and easily secured to the box and cover without the use of screws, rivets or other similar fastening elements. The invention can be embodied in boxes and hinges of various materials.

10 It is desirable that the hinge be made, at least in part, of springy or resilient material. The box and cover may be made of any desired material which is suitable for the purpose, such as wood, pulp, pressed metal, etc. The invention is of particular value in the case of boxes which are made by die-molding a suitable plastic. In forming articles of plastics such as bakelite which must be molded under conditions of high temperatures and pressures, it is necessary that the dies be of such a shape as to mold an article which will permit the retraction of the dies from each other in opposite directions after a molding operation. This limits to some extent the shapes which can be employed in making articles such as boxes and the like. It is an object of the invention to provide a hinge structure adapted to be mounted on a die-molded box without the use of screws, rivets, or other similar fastening elements. It is a further object of the invention to provide a box and cover of such a shape that they can be die-molded and will cooperate with such a hinge so that the resulting assembled structure is simple, strong, and easily assembled. These results are obtained by forming on the outside of a wall of the box, a shoulder under which a hook-shaped portion of a hinge member may catch, the hinge member having another portion engaging the inside of the wall so as to hold the hooked portion in engagement under the shoulder on the outside. This hinge member is preferably made of resilient material, such as spring metal, so that it can be readily snapped into place.

For a more complete understanding of the invention, reference may be had to the description thereof which follows, and to the illustration thereof on the drawing, of which,—

Figure 1 is a perspective view of a flanged box cover embodying the invention, a portion being broken away to illustrate the shape of the rear flange.

Figure 2 is a perspective view of a box embodying the invention, a portion of the rear wall being broken away to show in section.

Figure 3 is a perspective view of a hinge made according to the invention and adapted to be

assembled with the box and cover shown in Figures 1 and 2.

Figure 4 is a fragmentary rear end elevation of the assembled box, cover, and hinge.

Figure 5 is a section on the line 5—5 of Figure 4. 5

Figure 6 is similar to Figure 5, showing the cover in the course of being assembled with the hinge.

Figure 7 is a fragmentary section of a modified form of rear wall for a box. 10

Figure 8 is a fragmentary perspective view of another modified form of rear wall for a box.

Figure 9 is a perspective view of a box having slots in the side walls instead of a recess in the rear wall to receive a hinge member. 15

Figure 10 is a section of a modified form of box, cover, and hinge.

Figure 2 represents a box 10 which may be made of any suitable material, the shape being such that it can be made of a plastic such as bakelite molded in a high-pressure mold. The box includes a bottom 11, a front wall 12, side walls 13 and 14, and a rear wall 15. A portion of the rear wall may be especially formed with a rearwardly or outwardly extending bead 20 which projects 20 beyond the outer face 21 of the wall to form a downwardly facing shoulder 22. The upper part of the inside of the specially shaped portion of the rear wall is offset as at 23 from the lower inside surface 24 of the wall, forming a recessed area. 30 This results in a shoulder 25 which is undercut as at 26, forming a channel 30 which opens upwardly. The specially shaped portion of the rear wall may extend for the most part of the length of the rear wall, as illustrated in Figure 2, to receive 35 an elongated hinge such as is illustrated in Figure 3, or may be confined to one or more short lengths to accommodate one or more short hinges.

Figure 1 illustrates a cover 35 for the box 10, this cover having flanges 36 adapted to engage the upper edges of the walls of the box 10. As shown in the figure, the rear flange may have a portion shaped similarly to the specially shaped portion of the rear wall of the box, and corresponding thereto in length so as to receive the other member of the hinge which is attached to the box. To this end, the rear flange of the box cover may be provided with a rearwardly or outwardly projecting bead 37 forming an upwardly facing shoulder 40 on the outside of the cover. On the inside, an offset portion 41 of the inner surface of the rear flange forms a shoulder 42 which is undercut to provide a channel 43 opening downwardly.

Cooperating with the box and cover structure 55

illustrated, I provide a hinge which may consist of two similar members 50 and 51. Each of these members may, if desired, be formed from a sheet of spring metal, a suitable blank being first cut to shape. This blank is then bent to form knuckle portions 52 adapted to surround a hinge pin 53 about which as an axis the members 50 and 51 rock relatively to each other. Each member, in addition to the knuckle portions 52, 10 includes a pair of jaw members 55, 56, which project laterally from the pin 53. The jaw member 55 may be for the most part a flat plate adapted to lie against the offset portion 23 of the inner surface of the rear wall, the lower marginal portion 57 of the jaw 55 being seated in the channel 30. The jaw member 56 is provided with one or more portions projecting toward the jaw portion 55 so as to form a hook portion adapted to engage under the shoulder 22. As 15 shown in Figure 3, this hook portion may take the shape of a flange 60 along the lower edge of the jaw member 56, the flange being bent at right angles to project toward the member 55. The hinge is assembled with a box cover as indicated in Figure 6. Since the hinge members are 20 of resilient material, the jaws 55 and 56 may be sprung apart to permit the jaw 56 to pass the bead 20 of the box or the bead 37 of the cover, these beads preferably having a rounded edge 25 62 to facilitate the assembling of these members. When the flange 60 passes beyond the bead, it snaps under the corresponding shoulder and is not removable therefrom except by the application of a suitable tool or by the application of 30 destructive force to the hinge. The marginal portion 57 of the jaw member 55 seats in the channel 30 in the box or in the channel 43 in the cover and prevents the jaw 55 from springing away from the surface against which it normally 35 lies, when the cover is thrown back. It is evident from Figure 5 that once the hinge is properly assembled with the box and the cover, it forms a strong and permanent connecting link between the box and its cover.

40 45 As indicated in Figure 7, the shoulder 22 may be formed by cutting or sawing a kerf 65 in the rear wall of the box or in the rear flange of the cover. This kerf is thus in lieu of the bead 20 or 37, but requires an extra manufacturing operation.

50 As illustrated in Figure 8, the vertically extending shoulders between the offset portion 23 of the inner surface of the rear wall and the rest of this inner surface, are undercut to form channels 66 and 67, these channels opening toward each other and serving to anchor the jaw member 55 of the hinge. This form of anchorage is suitable for relatively short hinges, the horizontal channels 26 being preferable for long 55 60 hinges.

65 70 A slightly different form of box embodying the invention is shown in Figure 9. In this case, the inner surface of the rear wall of the box is not recessed but vertical channels 70 adjacent to this wall are formed in the side walls to receive and anchor a hinge member 55 after the manner of the channels 66 and 67 shown in Figure 8. This permits a thinner rear wall since no extra thickness is required to provide for a recessed or offset portion as in the forms shown in Figures 2 and 8.

75 Instead of a flanged cover as shown in Figure 1, a box may be provided with a flat cover 80 as shown in Figure 10. To accommodate such a cover having a length and width equal to the outside length and width of the box, the jaw

members of the hinge which engage the box wall may be bent as shown at 81 so that the hinge pin is rearward of the box wall and not between the box and cover.

It is evident that many alterations and changes 5 may be made in the specific details of the structure herein described and illustrated without departing from the spirit or scope of the invention as defined in the following claims.

I claim:—

10 1. A hinge comprising two members rockable relatively to each other about an axis, one of said members having two spaced portions projecting laterally from said axis, one of said portions having the margin along its free edge bent to form 15 a flange projecting toward the other said portion.

2. A hinge comprising a pair of members rockable relatively to each other about an axis, one of said members consisting of a sheet of spring metal shaped to form a pair of jaws, one jaw 20 having a terminal flange projecting toward the other jaw, said other jaw being disposed in a single plane.

3. A hinge comprising a pin, a pair of members rockable relatively to each other about the pin 25 as an axis, each said member consisting of a sheet of spring metal bent around said pin and projecting laterally therefrom to form a pair of jaws, and a flange on one jaw of each member projecting toward the other jaw of the same member, each of said other jaws being disposed in a single plane.

30 4. A box having a bottom and side walls, one of said walls having a downwardly facing shoulder on the outside thereof, in combination with 35 a hinge having a member with two jaws, the outer jaw having a hook portion engaging under said shoulder, the inner jaw projecting downwardly within said box, said box being formed with a channel in one of said walls in which a 40 marginal portion of said inner jaw engages.

5. A box having a bottom and side walls, one of said walls having a downwardly facing shoulder on the outside thereof, in combination with 45 a hinge having a member with two jaws, the outer jaw having a hook portion engaging under said shoulder, the inner jaw lying against the inner surface of the externally shouldered wall, said box having an inner channel adjacent to the inner wall surface engaged by said inner jaw, a 50 marginal portion of said inner jaw engaging in said channel.

6. A box having a bottom and side walls, one said wall having on its outside a downwardly facing shoulder and on its inside a recessed area 55 with a flange overhanging a marginal portion thereof to form a channel, in combination with a hinge member having a hooked portion on the outside of said wall engaging under said shoulder and a second portion inside said wall engaging 60 under said flange.

7. A box having a bottom and side walls, one said wall having on its outside a projecting portion forming a downwardly facing shoulder and on its inside an upwardly opening channel, in 65 combination with a hinge member having a hooked portion on the outside of said wall engaging under said shoulder and a second portion on the inside of said wall seated in said channel.

8. A box having a bottom and side walls, one 70 of said walls having an external shoulder facing downwardly and a plane inner surface, said box being formed with a pair of vertical inner channels in the walls adjacent to the shouldered wall at the junction of said walls, whereby one side 75

5 of each channel is a continuation of the inner plane surface of said shouldered wall, in combination with a hinge having a member with an inner and an outer jaw, the outer jaw being hooked under said shoulder, the inner jaw lying against said plane surface with marginal portions fitting in said channels.

10 9. A box having a side wall, in combination with a hinge therefor, said hinge and the outside of said wall having interengaging elements arranged to prevent upward movement of the hinge element relative to said wall, said hinge having a flat member disposed against the inner face of said wall, and means within the box and forming 15 a part thereof engaging the marginal portion of

said flat member and preventing movement of said member away from the inner face of said wall.

10 10. A box having a side wall and cover adapted to be connected by a hinge, external beads on the mutually adjacent marginal portions of said wall and cover, and a hinge comprising a pin and two members relatively rockable thereon, said members each consisting of a pair of jaws of resilient material sprung over said respective beads and positively held thereby, said beads having sufficient width to require springing the jaws of each pair apart for a substantial distance to receive the beads.

HANS H. WANDERS. 15
